UNITED STATES PATENT OFFICE.

JOHN A. LELAND, OF MONTAGUE, MASSACHUSETTS, ASSIGNOR TO MILLERS FALLS COMPANY, OF MILLERS FALLS, MASSACHUSETTS, A CORPORATION OF MASSACHUSETTS.

MITER-BOX.

1,159,396.

Specification of Letters Patent.

Patented Nov. 9, 1915.

Application filed January 9, 1915. Serial No. 1,336.

To all whom it may concern:

Be it known that I, JOHN A. LELAND, a citizen of the United States, and resident of Montague, in the county of Franklin and State of Massachusetts, have invented certain new and useful Improvements in Miter-Boxes, of which the following is a specification.

This invention relates to a miter box provided with a horizontal bed interrupted by an angular opening and a swinging bar pivoted at the apex of said opening and having saw guiding posts at its opposite end portions, the bar being adjustable to guide a saw at various angles relatively to the bed.

The invention has for its object to provide certain improvements relating to the means for confining the swinging bar in various positions, to the construction of the bar whereby its length may be varied and maintained without liability of accidental change in length, to the construction of the saw-guiding posts on the swinging bar, and to the construction of the frame.

The invention consists in the improvements which I will now proceed to describe and claim.

Of the accompanying drawings forming a part of this specification: Figure 1 represents a front elevation of a miter box embodying my invention; Fig. 2 represents a top plan view of the same; Fig. 3 represents a section on line 3—3 of Fig. 2; Fig. 3^a represents a view similar to a portion of Fig. 3, showing a different position of the detent lever; Fig. 4 represents a section on line 4—4 of Fig. 1; Fig. 5 represents a section on line 5—5 of Fig. 1, and a bottom plan view of parts above said line, other parts being omitted; Fig. 6 represents a fragmentary perspective view showing parts of the swinging bar, the detent lever hereinafter referred to, and other parts of the box; Fig. 7 represents in perspective certain parts hereinafter referred to; Fig. 8 represents a perspective view of the telescopic swinging bar in its contracted adjustment; Fig. 9 represents a view similar to a portion of Fig. 8, showing the swinging bar elongated; Fig. 10 represents a section on line 10—10 of Fig. 8; Fig. 11 represents a section on line 11—11 of Fig. 2; Fig. 12 represents a view similar to a portion of

Fig. 11, showing the sliding post member supported in a raised position; Fig. 13 represents in separate views the tube from which the sliding post member is made, said tube being shown in perspective, and a side elevation of the tube after it has been slotted as hereinafter described; Fig. 14 represents in separate views the upper end portion of the sliding tube member before and after the upper ends of its slots have been closed by the plug hereinafter referred to; Fig. 15 represents a section on line 15—15 of Fig. 1.

The same reference characters indicate the same or similar parts in all the views.

The frame of my improved miter box includes two supporting end members, each formed as a single casting, preferably of malleable iron, and each composed of a vertical web 12 and a flange 13 formed thereon, as indicated by Figs. 4 and 5, each member including a pair of legs having feet 14 adapted to bear on a bench. The frame also includes two horizontal bed members 16, each having a downwardly projecting marginal flange 17, said flanges being connected by rivets 18 with the flanges 13 of the end members. Each bed member and its flange is made of a single piece of relatively thick pressed sheet metal, preferably steel, the inner end 19 of each bed member being oblique and said oblique ends forming the edges of an angular opening between the bed members, as shown by Fig. 2. The frame also includes a central member of skeleton form, preferably formed as a single casting and including flanges 20 and 21 (Fig. 5) secured by rivets 22 to the flanges 17 of the bed members. The central frame member includes a socket 23 which, in this embodiment of the invention, is internally threaded to engage the thread portion of a pivot stud 24, which pivotally connects the swinging radius bar 25, hereinafter described, with the frame. On the socket 23 is formed an arcuate frame or inner bearing member 26, and said socket is connected by radial arms 27 with an intermediate arcuate bearing member 28 and an outer bearing member 29. The functions of the bearing members 26, 28 and 29 will be presently described, it being sufficient for the present to say that said members, the

socket 23, the flanges 20 and 21, and the arms 27, form a rigid skeleton frame which rigidly connects the two bed members 16 by reason of the fact that the flanges 20 and 21 are permanently secured to the flanges of the bed members by the rivets 22, or any other suitable means.

The frame construction as described is very strong and durable, and composed of 10 only five general parts, namely, the two supporting flanged end members, the two flanged bed members, and the skeleton central member.

The work to be sawed is supported vertically by the horizontal bed members and is held against two vertical back rests 28, which are pieces of pressed sheet steel attached by screws 29 to the rear edge of the frame and separated from each other by a narrow space 20 30 (Fig. 2) through which the saw passes. The back rests 28 are embossed to form alternating inclined recesses 28^a and projections 28^b (Figs. 1 and 2), the rests 28 therefore being corrugated and their corrugations 25 being inclined. The inclination of the corrugations of one rest is opposite that of the corrugations of the other rest, as shown by Fig. 1. I find that corrugations thus arranged tend to hold the work against upward 30 displacement from the bed members, the inclined edges of the projections 28^b resisting upward displacement of work bearing against the back rests.

The radius bar 25 is pivoted to swing on 35 the fixed stud 24, and is provided at its opposite end portions with inner and outer saw-guiding posts, each of telescopic construction and including a vertically immovable tubular member 31 secured to the bar, 40 and a vertically movable member 32, the latter embodying an improved construction hereinafter described. The bar is also of telescopic construction, and its body or main portion 25, which I call the inner section, is 45 longitudinally immovable and has only a swinging movement on the stud 24. Said inner section is supplemented by a slidable outer section carrying the outer saw-guiding post. The said outer section is composed of 50 a block 25^a to which are attached by rivets 33 (Fig. 15) two elongated spaced-apart clamping slides 34. The inner section 25 has grooves in the opposite edges of its outer end portion forming elongated guides 35 for the 55 slides 34 and frictional clamping faces 36 between said guides. 37 represents a bar having offset ends, one of which is attached at 38 (Figs. 10 and 15) to one of the slides 34. The other offset end overlaps the other 60 slide 34 and has a strut 39 bearing on the last mentioned slide and having a beveled outer end 39^a (Fig. 15).

40 represents a spindle which is rotatable and movable endwise in a guiding stud 41 attached to the block 25^a, and is provided

with a knurled head 42. One end portion of said spindle is threaded and engaged with a tapped orifice in the bar 37, the spindle having a conical tip 40^a bearing on the beveled end 39^a of the strut. Rotation of the spindle 40 in a direction to advance it into the bar 37 forces the strut 39 inwardly and presses the clamping slides 34 firmly against the faces 36, thus confining the outer section of the swinging bar at any position to which it may be adjusted. A rotation of the spindle in the opposite direction releases the said outer section, which is then free to move endwise. Provision is therefore made for securely maintaining the outer post at any desired distance from the inner post.

The elongated guides 35 on the opposite edge portions of the inner section 25, and the slides 34 engaged with said guides constitute a connection between the inner and outer sections of the bar adapted to firmly support the outer section at various distances from the inner section with the outer saw guide in a vertical position and free from liability to tip or spring laterally. The slides 34 and 90 the block 25^a collectively constitute a rigid sliding bar section adapted to resist torsional strain tending to tip or incline the outer saw guide. The engagement of the slides 34 with two opposite edge portions of the inner section 25 enables the bar as a whole to have an oblong horizontally elongated cross section, as indicated by Figs. 6, 8, 9 and 10, the material being so distributed that the thickness of the bar or the distance between 100 its top and bottom surfaces is reduced to the minimum. In other words, the bar is made relatively thin, so that the vertical space required for it and the height of the supporting frame are correspondingly reduced. The 105 thinness of the bar is compensated for by its width, which is much greater than its thickness and is sufficient to enable the various orifices shown by Fig. 3 to be formed in the inner section without unduly weakening said section.

I have provided means, including the inner arcuate member 26 and the intermediate arcuate member 28, for frictionally securing the swinging bar 25 in any angular position 115 that may be desired, said arcuate members forming fixed elements of said means, the other elements hereinafter described being carried by the swinging bar.

The fixed arcuate members 26 and 28 have upwardly facing bearing surfaces which, as shown by Fig. 3, are in frictional contact with a movable pressure block 42 carried by the swinging bar 25. One end portion of the pressure block has a downwardly projecting stud 43 passing loosely through the bar 25 and having a head 44 bearing on the under side of said bar. An expansion spring 45 bearing at its lower end on the bottom of a socket in the bar 25 bears at its upper end 125 130

on the longer arm of a pressure transmitting lever 47, the fulcrum of which is formed by the head of a stud 48 screwed into the bar 25, the lever 47 having a slot 49 (Fig. 7) in one end receiving a rod 63, and a slot 50 in the other end receiving the stud 48. A stud 51 attached to the pressure block 42 projects through the slot 50 and has a shoulder 52 which is preferably an adjustable nut bearing on the under side of the shorter arm of the lever 47, the stud 51 being screw-threaded to engage said nut.

53 represents a detent lever which is pivoted at its inner end at 54 to an ear on the radius bar 25 and is pressed upwardly by a spring 55 against the outer arcuate member 29, said lever being located above the radius bar and its free end being over the outer portion of said bar. Said arcuate member has a series of notches 57 in its lower edge and flat faces 56 between said notches. The upper edge of the detent lever is formed to enter a notch 57, as shown by Figs. 3 and 6, and thus positively lock the bar 25 against swinging movement. Said upper edge is also adapted to bear against either of the flat faces 56, as shown by Fig. 3^a. The expansion spring 45 acts through the pressure transmitting lever 47 on the nut 52, and through the latter and the stud 51 to cause a strong downward pressure of the pressure block 42 on the arcuate members 26 and 28. The friction developed by this pressure confines the bar 25 with sufficient firmness to prevent it from swinging unless relatively heavy force is exerted against it, the frictional confinement being sufficient to prevent accidental movement of the bar under ordinary usage.

40 To reduce or interrupt the frictional bar-confining pressure and permit the bar to swing easily, I provide a pressure-reducing lever 60, which is fulcrumed on the head 61 of a stud attached to the bar 25, one arm of said lever being much longer than the other, as shown by Fig. 3. The lever 60 is located below the radius bar, and its free end is below the outer portion of said bar and in close proximity to the free end of the detent lever, so that said levers are manually movable simultaneously in opposite directions by one hand of the operator. The shorter arm of the lever 60 has a slot 62^a (Fig. 7), which receives the stud 62, and the lower end of a rod 63. Said rod passes through the spring 45 and the longer arm of the pressure transmitting lever 47, and has a pin 64 at its lower end bearing on the lever 60, and a pin 65 at its upper end bearing on the lever 47. Upward pressure on the longer arm of the pressure-reducing lever 60 depresses the rod 63, compresses the spring 45, and renders the latter inoperative, and at the same time depresses the longer arm of the lever 47, so that the pressure block 42 is free to slide on

the fixed members 26 and 28, and the bar 25 is adapted to swing without material frictional resistance.

The detent lever extends outwardly across the under side of the notched member 29, and projects from the front of the miter box, so that its outer end is exposed and is manually movable to withdraw the lever from a notch 57. The outer end of the detent lever is provided with an upwardly facing thumb rest 67. The outer arm of the pressure-reducing lever 60 extends outwardly to a point under and in relatively close proximity to the outer end of the detent lever, and is adapted to be manually raised to depress the inner arm and render the spring 45 inoperative. Said longer arm is provided with a downwardly facing finger rest 68. Said rests are in convenient proximity to each other, as shown by Fig. 3, so that the operator may apply a thumb to one rest and a finger to the other and exert pressure on both rests by the same hand to simultaneously move the levers in opposite directions and free the radius bar from all resistance to its swinging movements, each rest being preferably formed in duplicate, as shown by Figs. 2 and 6, so that the operator may selectively apply the described pressure.

The vertically movable member 32 of each saw-guiding post is made from a seamless metal tube 32^a (Fig. 13), in opposite sides of which are formed longitudinal slots 70 extending from one end partly to the opposite end of the tube, one end portion being continuous. The upper ends of the slots 70 have enlargements 70^a forming two sides and the lower end of a sawback guide. A plug 71 inserted in the upper end of the tube and secured by a rivet 72 closes the upper end of the tube and forms the upper end of the saw back guide. The movable post member thus constructed is at once light, strong and durable, and is adapted to slide freely in the vertically immovable member 31.

The member 32 has the usual stop member 73 which limits its downward movement, as shown by Fig. 11, and the member 31 has the usual spring-pressed latch bolt 74 adapted to enter a notch 75 in the member 32, and limit the upward movement of the latter, as shown by Fig. 12.

As implied in the foregoing description and in the following claims, I am not limited to the specific mechanism of the preferred embodiment of my improvements shown by the drawings except as otherwise required in certain of the more limited claims.

125 Having described my invention, I claim:

1. In a miter box, the combination of a work-supporting frame having a fixed arcuate notched member, a radius bar provided with saw guides and pivoted to the

frame, a notch-engaging detent lever fulcrumed at its inner end on said bar and extending outwardly across the under side of the notched member, the outer end of said lever being exposed and adapted to be manually depressed to disengage the lever from the notched member, a spring carried by the bar, means coöperating with said spring to confine the bar in various positions by friction, and a pressure-reducing lever located below and fulcrumed on the bar and having a shorter inner arm connected with said spring and an outwardly extending longer arm, the outer end of which is exposed below the outer end of the detent lever and adapted to be manually raised to render said spring inoperative.

2. In a miter box, the combination of a work-supporting frame having a fixed arcuate notched member, a radius bar provided with saw guides and pivoted to the frame, a notch-engaging detent lever fulcrumed at its inner end on said bar and extending outwardly across the under side of the notched member, the outer end of said lever being exposed and provided with an upwardly facing rest whereby it may be manually depressed to disengage the lever from the notched member, a spring carried by the bar, means coöperating with said spring to confine the bar in various positions by friction, and a pressure-reducing lever located below and fulcrumed on the bar and having a shorter inner arm connected with said spring and an outwardly extending longer arm, the outer end of which is exposed below the outer end of the detent lever and provided with a downwardly facing rest whereby it may be manually raised to render said spring inoperative.

3. In a miter box, the combination of a work-supporting frame having an angular opening, fixed inner, outer and intermediate arcuate members extending across said opening, the said inner and intermediate members having continuous upwardly facing bearing surfaces, while the outer member is notched, a radius bar pivoted to swing on a vertical axis concentric with said bearing surfaces, and provided with saw guides, a notch-engaging detent lever fulcrumed at its inner end on said bar and extending outwardly across the under side of the notched member, the outer end of said lever being exposed at the front of the box and adapted to be manually depressed to disengage the lever from the notched member, a spring carried by the bar, an elongated movable pressure block adapted to bear on said inner and intermediate members, a pressure-transmitting lever fulcrumed on the bar and having a longer and a shorter arm, said longer arm forming an abutment for said spring, a connection between the shorter arm of said transmitting lever and the pressure

block, through which the pressure of the spring is exerted on the block to frictionally confine the bar, and a pressure-reducing lever located below and fulcrumed on the bar, and having a shorter inner arm connected with said spring, and an outwardly projecting longer arm, the outer end of which is exposed at the front of the box and is adapted to be manually raised to render said spring inoperative.

4. A miter box, comprising a work-supporting frame, a telescopic radius bar composed of a relatively thin and wide inner section pivoted to the frame, and provided with an inner saw guide at its inner end portion, external edge guides at opposite edges of its outer end portion, and external frictional clamping faces between said guides, and an outer section composed of a block provided with an outer saw guide, and with elongated clamping slides attached to its opposite edges and bearing on the edge guides and frictional faces of the inner section, and manually operable means carried by said outer section and slides for clamping said slides against the friction faces of the inner section.

5. A miter box, comprising a work-supporting frame, a telescopic radius bar composed of a relatively thin and wide inner section pivoted to the frame, and provided with an inner saw guide at its inner end portion, external edge guides at opposite edges of its outer end portion, and external frictional clamping faces between said guides, and an outer section composed of a block provided with an outer saw guide, and with elongated clamping slides attached to its opposite edges and bearing on the edge guides and frictional faces of the inner section, a transverse bar having offset ends, one of which is attached to one of the slides, said bar bridging the space between the slides so that its other offset end overlaps the other slide, a guiding stud attached to the outer section, a spindle rotatable in said stud and having a threaded portion engaged with a tapped orifice in the overlapping offset end of said bar to cause endwise movement of the spindle when the latter is rotated, said spindle having a conical inner end and an exposed knob or handle at its outer end, whereby the spindle may be rotated, and a strut movable in said overlapping end and bearing on the adjacent slide to frictionally engage the slides with the inner section.

6. In a miter box, a saw guiding and supporting post member composed of a seamless metal tube having longitudinal slots formed in opposite sides and extending from one end partly to the opposite end, the latter being continuous, the slots being enlarged at one end of the tube to form the sides and inner end of a saw back guide, and a plug

inserted in the enlarged ends of the slots and secured to the tube to form the outer end of the back guide, said member being vertically movable in a vertically immovable post member.

7. A miter box frame, comprising two supporting end members having legs, and each formed as a single casting including a body web and a flange, two bed members of 10 pressed sheet metal, each including a horizontal body portion and a downwardly projecting flange, the flanges of the bed members being riveted to the flanges of the supporting end members, and the body portions 15 of the bed members having oblique inner ends forming the edges of an angular opening in the frame, and a central frame member of skeleton form riveted to the flanges of the bed members and forming a rigid 20 connection between the latter, said central member having means for pivotally supporting a saw-carrying bar.

8. A miter box frame, comprising two supporting end members having legs, and 25 each formed as a single casting including a body web and a flange, two bed members of pressed sheet metal, each including a hori-

zontal body portion and a downwardly projecting flange, the flanges of the bed members being riveted to the flanges of the supporting end members, and the body portions of the bed members having oblique inner ends forming the edges of an angular opening in the frame, a central frame member of skeleton form riveted to the flanges of 30 the bed members and forming a rigid connection between the latter, said central member having means for pivotally supporting a saw-carrying bar, and sheet metal back rests attached to the said frame members. 35

9. A miter box frame, comprising a horizontal work-supporting bed having an angular opening, and vertical back rests at the inner edge of the bed and separated from each other at the apex of said opening, said 40 back rests being composed of pressed sheet metal plates having inclined corrugations.

In testimony whereof I have affixed my signature, in presence of two witnesses.
